METHOD OF CONTROLLING COILING MACHINES

Wentworth D. Boynton, Woodbrook, Md., assignor to Western Electric Company, Incorporated, New York, N. Y., a corporation of New York

Application April 30, 1948, Serial No. 24,407

3 Claims. (Cl. 242—25)

1

This invention relates to methods of controlling coiling machines, and more particularly to methods of controlling a coiling machine so that it produces coils each containing a predetermined length of a filamentary article.

In the manufacture of filamentary articles, such as insulated conductors, the finished product generally is wound into coils, each of which is intended to be made up of a specified length of the filamentary article. In general, coiling machines used for this purpose are so controlled that the motor driving the coiling machine is deenergized after a predetermined number of feet of a filamentary article has been coiled thereby, whereupon the coiling machine is allowed to coast to a stop. The coiling machine in coasting to a stop continues to coil up the filamentary article and, as a result, the final coil produced by the machine contains an additional length of the filamentary article above the specified footage. In order to prevent the coils taken up by the coiling machine from containing more than the predetermined footage required per coil, it is desirable to provide means for controlling the coiling machine, which will take into account in the coiling operation of each coil the coasting of the coiling machine.

An object of the invention is to provide new and improved methods of controlling coiling machines.

An apparatus by means of which methods embodying certain features of the invention may be practiced comprises a motor for driving a coiling machine, means for selectively energizing the motor to initiate a coiling operation, and means for deenergizing the motor energizing means each time a length of the filamentary article has been coiled up which is less than the desired length of the coil by an amount equal to the footage coiled up while the machine coasts to a stop, said coiling machine coasting to a stop to complete the coiling operation after the deenergization of the motor. As a result, each successive coiling operation of the coiling machine consists of a driven period and a coasting period which coact for each respective coiling operation to produce coils having uniform lengths of the filamentary article therein.

A clear understanding of the invention will be had from the following detailed description of specific embodiments thereof, when read in conjunction with the appended drawings, in which:

Fig. 1 is a front elevation of a combined twist-

2

ing, sparktesting, and coiling machine, including apparatus embodying certain features of the invention;

Fig. 2 is a front elevation, partially in section, of a control device shown in Fig. 1;

Fig. 3 is a vertical, sectional view taken along line 3—3 of Fig. 2;

Fig. 4 is a vertical, sectional view taken along line 4—4 of Fig. 3;

Fig. 5 is a wiring diagram of an electrical circuit used in connection with the apparatus shown in Fig. 2;

Fig. 6 is a front elevation of a control device comprising part of an alternating embodiment of the invention and having portions thereof broken away for clarity;

Fig. 7 is a left end view of the device shown in Fig. 5;

Fig. 8 is an enlarged, sectional view taken along line 8—8 of Fig. 6;

Fig. 9 is a wiring diagram of an electrical circuit used in connection with the device shown in Fig. 6;

Fig. 10 is a fragmentary, front elevation of another embodiment of the invention, and

Fig. 11 is a vertical, sectional view taken along line 11—11 of Fig. 10.

Referring now in detail to the drawings and more particularly to Fig. 1, an insulated conductor indicated by the numeral 10 is drawn from a supply reel 11 into a twisting machine indicated generally at 12 and having a rotatable flyer 13 driven by an electric motor 14 through a suitable gear reducer unit 15. Another supply reel 18 is positioned within the rotatable flyer 13 of the twister 12 and contains an insulated conductor 19, which is identical in size and construction with the conductor 10.

When the flyer 13 is rotated by the motor 14, it twists the conductors 10 and 19 together to form a twisted pair 20. After the twisted pair 20 emerges from the twister 12 it advances around an idler sheave 21, passes around a capstan 22 several times and then is drawn through a sparktesting apparatus 26. The twisted pair 20 then passes around a guide pulley 27 mounted on the end of a tension arm 28, around a pulley 30 carried by a suitable traversing mechanism 31 and finally to a rotatable coiling head 32 provided on one end of a pivotally mounted support 33 of a dual type coiling machine indicated generally at 34. The coiling machine 34 is fully disclosed and described in E. D. Hanson Patent 2,561,736, granted July 24, 1951, and

will be described herein only insofar as it is

55

necessary for a clear understanding of the invention.

The dual coiling machine 34 is provided with a second coiling head 35 which is rotatably mounted on the other end of the pivotally mounted support 33 and which may be positioned to receive the twisted pair 20 in place of the coiling head 32. The coiling machine 34 is provided with an electric motor 37 which is arranged to drive the particular coiling head positioned to receive the twisted pair 20, such as the coiling head 32, through a suitable gear reducer unit (not shown) and a clutch (not shown). A cover 36 is pivotally mounted on the coiling machine 34 so as to partially enclose the coiling head that is being driven by the motor to coil up the twisted pair 20.

The coiling machine 34 is provided with dual coiling heads 32 and 35 so that when one of the coiling heads has coiled up a predetermined footage of the twisted pair 20, it may be replaced by the empty coiling head and the machine continued in operation to coil up the twisted pair 20 while the previously wound coil is removed from the other coiling head.

A control device, such as is indicated generally at 40 (Figs. 1 and 2), is designed to operate at predetermined intervals to automatically deenergize the motors 14 and 37 driving the twister and the coiling machine, respectively, so that each coil taken up by the coiling heads will contain only a predetermined length of the twisted pair 20. Most of the mechanism of the control device 40 (Fig. 2), is the same as that of a conventional counter the construction and operation of which are well known, and, therefore, the construction of the control device will be described only insofar as is necessary for a complete understanding of the invention.

The control device 40 is positioned on a support 41 mounted on the gear reducer 23 and is driven by a shaft 42, which, in turn, is driven by suitable gearing (not shown) provided in the gear reducer 23. The shaft 42, through bevelled gears 44-44 (Fig. 3), drives a shaft 45 of the control device 40. The shaft 45, in turn, drives a vertical shaft 46 (Fig. 2) suitably journaled between the top and bottom walls of the control device 40 by means of bevelled gears 47-47. The shaft 46 drives a shaft 50 by means of a worm 51 secured on the shaft 46 and a worm gear 52 secured on the shaft 50. Counting wheels 53-53 are rotatably mounted on the shaft 50 and are driven by each other in the conventional manner, that is, each time the units counting wheel 53 is turned through one revolution by the shaft 50 it advances the tenths wheel 53 one digit, and each time the tenths wheel 53 completes one revolution it advances the hundredths wheel one digit. The shaft 50 is driven by the shafts 42, 45 and 46 in such a manner that the wheels 53-53 continuously record the footage of the twisted pair 20 taken up by the coiling machine when the motors are energized.

A cam 54 is mounted on the shaft 50 so as to be actuated by the hundredths wheel 53 of the control device, in the same manner that the hundredths wheel normally actuates the thousands wheel of a counting mechanism. The cam 54 is provided with ten equally spaced lobes 55-55, which are successively advanced each time the hundredths wheel completes one revolution. The periphery of the cam 54, including the lobes 55-55, is engaged by a roller 56 (Fig. 3) rotatably mounted on a shaft 57 secured between the

ends of a cam follower 60 pivotally mounted on a shaft 61 secured between the end walls of the control device. The cam 54 is positioned on the shaft 50 so that when the "0" digits of the counting wheels 53-53 are aligned with a window 62 provided in the front of the control device, a lobe 55 of the cam is directly under the roller 56 of the cam follower 60.

The cam follower 60 is provided with an elongated arm 63 (Figs. 3 and 4) projecting therefrom so that the free end thereof is directly over the free end of a lever 64 pivotally mounted on a sensitive switch 66 secured to a partition 67 provided in the control device 40. The lever 64 engages a plunger 68 of the switch 66, which actuates a normally open contact 69 (Fig. 5) provided in the switch 66. A tension spring 70 has one end thereof secured to the partition 67 and the other end thereof secured to the end of the arm 63 of the cam follower 60 and serves to urge the cam follower 60 downwardly and to maintain the roller 56 in engagement with the periphery of the cam 54.

Referring to Fig. 5 of the drawings, low potential busses 73 and 74 are supplied with suitable potential by the secondary winding of a transformer 76 having its primary winding connected across one phase of a three-phase circuit connected to a source of three-phase potential indicated by the terminals 77-77. The three-phase circuit connected to the terminals 77-77 serves to supply three-phase potential to the twister motor 14 through normally open contacts 78-78 provided on an electromagnetic contactor 80 indicated generally at 80. The operating coil 81 of the contactor 80 is connected across the busses 73 and 74 in series with a normally closed "stop" push button 82, a normally open "start" push button 84 and a normally closed contact 85 provided on a relay indicated generally at 86. The contactor 80 is provided with a normally open contact 87, which serves to bridge the normally open start button 84, once the coil 81 of the contactor 80 is energized by a momentary closure of the start button.

The contactor 80 is provided with a second normally open control contact 88, which serves to connect an operating coil 90 of a contactor 91 across the busses 73 and 74 through the normally closed contact 85. The contactor 91 is provided with normally open contacts 92-92, which serve to control the continuity of a second three-phase circuit connected to the three-phase supply terminals 77-77 and to the coiling machine motor 34. An operating coil 93 of the relay 86 is connected across the busses 73 and 74 in series with the normally open contact 69 of the switch 66, and a normally closed push button contact 95. The contact 69 of the switch 66 is moved at intervals into an open position by the lobes 55-55 of the cam 54, against the action of the spring 70. The relay 86 is provided with a normally open contact 96, which is connected in parallel with the normally open contact 69 of the switch 66.

Operation

Assuming that a reel 11 containing a supply of the conductor 10 and a reel 18 containing a supply of the conductor 19, have been placed in their respective positions, the conductors 10 and 19 are threaded through the apparatus, the ends thereof are secured to the coiling head 32, and the coiling head cover 36 is moved into the position shown on the drawings. Let it also be as-

sumed that the control device 40 is adjusted at the start of a series of coiling operations so that the "0" of each of the wheels 53-53 is aligned with the window 62; and that the coils to be wound by the coiling machine 34 are to contain 1000' of the twisted pair 20.

The start button 84 is actuated, which places the operating coil 81 of the contactor 80 across the control busses 73 and 74, thereby energizing the coil 81 and closing the contacts 78-78 of the contactor 80 to connect the twister motor 14 directly to the three-phase supply terminals 77-77. This energization of the motor 14 rotates the flyer 13 to twist the conductors 10 and 19 together to form the twisted pair 20. The normally open contact 81 of the contactor 80 also is closed upon the energization of the coil 81, and serves to maintain the coil 81 connected across the busses 73 and 74 when the start button 84 is released.

The normally open contact 88 of the contactor 80 also is closed, thereby placing the operating coil 90 of the contactor 91 across the busses 73 and 74. The energization of the coil 90 closes the contacts 92-92 and connects the motor 37 across the three-phase supply terminals 77-77, whereby the motor 37 is energized and drives the coiling head 32. The actuation of the "start" push button 84 energizes the motors 14 and 37 in the above-described sequence to initiate a coiling operation of the coiling head 32, whereupon the twisted pair 20 produced by the flyer 13 is drawn from the twister 12 by the capstan 22, then passes through the high voltage sparktesting apparatus 26 around the pulley 30 provided on the distributing mechanism 31 and finally is coiled up by the ceiling head 32.

The control device 40 is driven by the shaft 42, through the gear reducer 23 in such a manner, that each time the coiling head 32 takes up one foot of the twisted pair 20, the units wheel 53 advances one digit. The units counting wheel 53 of the control device 40, in turn, advances the tenths and hundredths wheels digit by digit as each counting wheel of a lower order completes one revolution. The apparatus continues to operate until the hundredths wheel 53 of the counter has made one complete revolution, in which case, as the hundredths wheel moves from "9" to "0," with respect to the window 62, it moves the cam 54 one-tenth of a revolution, that is, the distance between two of the lobes 55-55, since there are ten lobes on the cam.

Upon this movement of the cam 54, the spring 70 causes the roller 56 provided on the cam follower 60 to enter the depression in the periphery of the cam between the next successive lobes 55-55, whereupon the arm 63 of the cam follower 60 moves downwardly and strikes the lever 64 of the switch 66. The lever 64 is moved downwardly thereby and presses the plunger 68, which closes the normally open contact 69 of the switch 66. When the cam 54 advances one lobe there will be only a momentary closure of the contact 69 because the next succeeding one of the lobes 55-55 stops directly under the roller 56 and holds the arm 63 out of engagement with the lever 64 when the cam comes to rest.

Closure of the contact 69 connects the operating coil 93 of the relay 86 across the busses 73 and 74, whereby the coil 93 is energized and opens the normally closed contact 85 and closes the normally open contact 96. The opening of the contact 85 breaks the circuit to the operating coils 81 and 90 and thereby causes the contactors 80 and 91 to drop open simultaneously to disconnect

the motors 14 and 37 from the terminals 77-77 and thereby terminate the driven portion of the coiling operation of the coiling head 32. The closure of the contact 96 of the relay 86 bridges the contact 69 of the switch 66 and maintains the coil 93 energized after the momentary closure of the contact 69 has occurred.

Upon the simultaneous deenergization of the motors 14 and 37, the coiling head 32 and the twister 12 coast to a stop, and in so doing, the coiling head 32 coils up additional footage of the twisted pair 20. At the point at which the control device advanced the cam 54 to deenergize the motors 14 and 37, the "0" of each counting wheel 53-53 was aligned with the window 62 and the coiling head 32 had taken up 1000' of the twisted pair 20 which is the length of the twisted pair required per coil. Therefore, when the apparatus comes to a stop, the coil contains the total footage of the twisted pair 20 which was taken up by coiling head 32 during the driven portion and the coasting portion of the coiling head 32, in which case the coil on the coiling head 32 contains more of the twisted pair 20 than is required per coil. Assuming that the coasting period of the apparatus is such that coiling head coils up six feet of the twisted pair 20 as the apparatus coasts to a stop, the coil taken up by the coiling head 32 in the initial coiling operation contains one thousand and six feet of the twisted pair 20 or six feet above that required per coil.

Since the wheels 53-53 of the control device had completed a predetermined measuring period during which the coiling head 32 coiled up 1000' of the twisted pair 20 at the point when the motors were deenergized, the control device was in position to begin another of its predetermined measuring periods. As the apparatus coasts to a stop, the control device which is driven by the shaft 42 continues to measure the footage of the twisted pair being coiled up thereby. Thus, when the apparatus stops the coasting period will have consumed a portion of the successive predetermined measuring period which began upon the deenergization of the motors; in which case the control device now indicates only the footage of the twisted pair coiled up during the coasting period of the coiling head 32. If, as assumed above, the coasting of the apparatus takes up six feet of the twisted pair, the digit "6" of the units wheel 53 is aligned with the window 62 at the end of the initial coiling operation of the coiling head 32.

After the apparatus has stopped, the cover 36 is moved to its broken line position, shown in Fig. 1 of the drawing, and the twisted pair 20 is severed adjacent to the coiling head 32. The support 33 then is rotated to locate the coiling head 35 in position to receive the twisted pair 20 and be driven by the motor 37. The loose end of the twisted pair 20 is secured to the coiling head 35 in a suitable manner, and the cover 36 is returned to its normal operating position. The "start" button 84 is actuated to initiate the coiling operation of the coiling head 35 in the manner described above for the coiling head 32.

The twisting, sparktesting and coiling operations continue until the wheels 53-53 have completed the remaining portion of their predetermined measuring period, whereupon the "0" of each wheel of the control device again is aligned with the window 62, and the cam 54 again is advanced one lobe. This movement of the cam again allows the arm 63 of the cam follower 60 to close

the normally open contact 69 of the switch 66. The momentary closure of the contact 69 energizes the relay 86, deenergizes the contactors 80 and 91, and disconnects the motors 14 and 34 from the three-phase supply terminals 77, whereupon the apparatus coasts to a stop to complete the coiling operation of the coiling head 35.

At the end of the next preceding coiling operation, the units wheel of the control device 40 had been advanced an amount equivalent to the length of the twisted pair 20 that was coiled on the coiling head 32 while the apparatus was coasting to a stop. Consequently, at the point at which the cam 54 was advanced one lobe by the hundredths wheel 53 and the motors 14 and 37 were deenergized to terminate the driven portion of the coiling operation of the coiling head 35, the coil on the coiling head 35 lacked the required 1000' of the twisted pair 20. However, after the motors are deenergized by the movement of the cam 54, the apparatus again coasts to a stop and in so doing continues to coil up additional footage of the twisted pair 20. Since the amount the apparatus coasts each time the motors are deenergized is practically constant throughout a series of coiling operations, the length of twisted pair that is coiled during each coasting period of the apparatus is substantially equal to the footage of the twisted pair that the coil lacks at the point at which the motors are deenergized, whereby each completed coil, after the first one, contains the required 1000' of the twisted pair.

On the basis of the assumption that the coasting of the apparatus takes up six feet of the twisted pair 20, when the coiling head 35 is placed in operation to coil up the twisted pair 20, the control device 40 registers six feet. In that case, when the coiling head 35 coils up only nine hundred ninety-four feet of the twisted pair 20, the control device 40 has completed its predetermined measuring period, whereupon the motors 14 and 37 are deenergized and the apparatus coasts to a stop to complete the coiling operation. Since the control device 40 continues to operate as the apparatus coasts to a stop, the control device will register six feet when the coiling head 35 stops, since the coasting of the machine is substantially uniform for each coiling operation. Therefore, the coil coiled up by the coiling head 35 contains the required one thousand feet of the twisted pair 20, because the coasting of the machine makes up the footage of the twisted pair 20 that the coil lacks when the motors were deenergized by the control device.

Each successive coiling operation of the coiling heads 32 and 35 consists of a period during which the coiling heads are driven by the motor 14 and a coasting period which add up for each complete coiling operation to produce coils having the required 1000' of the twisted pair 20. Thus, while the first coil taken up by the coiling head 32, when such apparatus is first placed in operation, contains an overrun of the twisted pair 20 caused by the coasting of the apparatus, each successive coil formed thereafter will contain only the predetermined footage of the twisted pair required per coil, whereby any waste of the twisted pair 20 in the coiling operation thereof is substantially eliminated.

1st alternative embodiment

Figs. 6, 7, 8 and 9 of the drawings show an alternative embodiment of the invention in which a control device 140 (Figs. 6 and 7) is mounted

on the support 41 in place of the control device 40, and is driven by the shaft 42 in the manner described for the control device 40.

The control device 140 is identical in construction and operation with the control device 40 except that a cam 154 having a single lobe 155 is positioned on the shaft 50 and actuated by the hundredths wheel 53 in place of the cam 54, and a resetting apparatus indicated generally at 200 is provided for quickly resetting the control device 140 to "0" upon each movement of the cam 154. The cam 154 is positioned on the device 140 so that the lobe 155 maintains the sensitive switch 66 normally open when the recording wheels of the device 140 register "0" with respect to the viewing window of the device.

The resetting apparatus 200 includes a bracket 201 secured on the left side of the control device 140 which is provided with a post 202. A segment 204 is rotatably mounted on the post 202 and is provided with internal teeth 205—205, which engage a pinion 206 keyed on the end of the shaft 150 of the control device 140. The segment 204 is provided with a splined hub 207, which engages a splined bore provided in the end of a reset lever 208. A pair of links 210—210 have one end thereof connected pivotally to the end of the lever 208 by means of a pin 211 and the other end thereof connected by means of a pin 212 to an armature 213. The armature 213 forms part of a conventional solenoid 215 having an operating coil 216, which, when energized, serves to pull the lever 208 downwardly, thereby resetting the counting wheels 53—53 and the cam 154 of the control device to their respective "0" positions. The solenoid 215 is mounted on a bracket 217 secured to the support 41 (Figs. 6 and 7).

Fig. 9 shows a schematic wiring diagram for the alternative embodiment of the invention which employs the control device 140. This diagram is identical with the diagram shown in Fig. 5 for the control device 40, except for the cam 154, and the coil 216 of the solenoid 215 connected in parallel with the coil 193 of the relay 186, which is arranged to be energized by closure of the switch 66 in the manner described for the relay 86 in the main embodiment of the invention.

Operation of 1st alternative embodiment

In the alternative embodiment of the invention, the control device 140 operates in the same manner as the control device 40, except for the fact that when the cam 154 is actuated by the device 140 to move its single lobe 155 to its broken line position shown in Fig. 8, the solenoid coil 216 is energized simultaneously with the deenergization of the motors 14 and 37 to quickly reset the control device to "0." The resetting of the control device 140 returns the cam 154 to its full line position shown in Fig. 8.

Upon the deenergization of the motors 14 and 37 by the movement of the cam 154, the apparatus coasts to a stop, and the coiling head continues to coil up the twisted pair 20. Therefore, the initial coiling operation performed by the coiling machine will produce a coil having more than the required footage of the twisted pair 20. Since the coasting of the apparatus continues to drive the control device 140, it will register at the completion of the initial coiling operation only the footage of the twisted pair taken up by the coasting of the apparatus. The control device remains in this partially actuated condition when the

second coiling operation is initiated, and when the cam 154 again deenergizes the motors, the coil on the coiling machine lacks the required footage of the twisted pair by the amount taken up by the previous coasting of the machine. However, the subsequent coasting of the apparatus following the deenergization of the motors, adds that footage of the twisted pair which the coil lacked at that point, and the final coil contains the predetermined footage of the twisted pair required per coil. 10

Since the control device 140 is instantaneously reset to its normal starting position upon the movement of the cam 154, which deenergizes the motors 14 and 37, the coasting of the apparatus which completes the coiling operation consumes a portion of the predetermined measuring period of the control device. But while this coasting of the apparatus consumes a part of the next operating period, it also adds to the coil in process of being coiled the footage of the twisted pair 20 that the coil lacks at the point at which the motors were deenergized. Consequently, each successive coil taken up by the coiling machine contains only the desired length of the twisted pair 20 and any excess of the twisted pair 20 in the coils is eliminated, except for the first coil produced in a given series of coiling operations. 20

2nd alternative embodiment

Figs. 10 and 11 of the drawings show another embodiment of the invention in which a control device 240 is mounted on the support 41 in place of the control device 40 and driven by the shaft 42 in the manner described for the control device 40.

The control device 240 is identical in construction with the control device 40 except that a cam 254 having a single dwell 255 is secured to the hundredths wheel 53 for rotation therewith, digit by digit, in a counterclockwise direction, when viewed in Fig. 11, instead of being positioned on the shaft 50 and advanced like the thousandths wheel of a counter. The cam 254 is positioned on the hundredths wheel of the device 240 so that the periphery of the cam maintains the sensitive switch 66 normally open when the counting wheels register "0" with respect to the window 62.

Operation of 2nd alternative embodiment

The control device 240 operates in the same manner as the control device 40 to determine the length of the twisted pair 20 to be coiled up during each coiling operation of the coiling heads 32 and 35, except for the fact that the cam 254 rotates with the hundredths wheel. Since the cam 254 has only the single dwell 255, it maintains the switch 66 closed until the cam and hundredths wheel make one complete revolution. The last movement of the hundredths wheel in completing one revolution moves the dwell 255 of the cam momentarily under the roller 56, whereupon the switch 66 is opened to deenergize the motors 14 and 37.

The apparatus then coasts to a stop to complete the coiling operation of the coil being coiled up, following the deenergization of the motors, and consumes a portion of the successive footage measuring period of the control device 240. The motors are deenergized by the device 240 in each successive coiling operation when the length of the twisted pair 20 which has been coiled up is less than the desired length per coil by an amount equal to that coiled up while the apparatus coasts to a stop. As a result the apparatus will produce 75

coils of the twisted pair 20 of uniform length throughout a series of coiling operations.

It is to be understood that the above described arrangements are merely illustrative of the application of the principles of the invention. Numerous other arrangements may be readily devised by those skilled in the art which will embody the invention and fall within the spirit and scope thereof.

While several kinds of control devices have been described for practicing methods embodying the invention in conjunction with an apparatus for twisting and coiling electrical conductors, such methods may be employed in coiling or winding various types of filamentary articles where it is required to produce a coil or package containing a predetermined length of the filamentary article. By the same token, the control devices may be designed to measure and produce coils of any desired length other than 1000', which length was used merely to illustrate the invention. Also they could be positioned to be driven directly by the travelling filament, instead of through the gear reducer described.

25 What is claimed is:

1. The method of controlling a motor driven machine for coiling filamentary articles to produce coils of substantially uniform length, which comprises energizing the motor driving the coiling

30 machine to initiate a coiling operation of the filamentary article initiating a predetermined footage measuring period of the filamentary article being coiled up simultaneously with the initiation of the coiling operation, deenergizing the motor driving the coiling machine when the predetermined measuring period has elapsed, allowing the coiling machine to coast to a stop, initiating a second footage measuring period of the filamentary article upon the deenergization of the motor 35 so that the coasting of the machine consumes a portion of a second footage measuring period, and repeatedly initiating successive coiling operations with a portion of each predetermined measuring period partially consumed by the coasting period 40 of the next preceding coiling operation and deenergizing the motor upon the expiration of its respective predetermined measuring period.

2. The method of controlling a machine for coiling filamentary article to produce coils of

50 uniform length, which comprises connecting motive power to the coiling machine to coil the filamentary article, simultaneously measuring the length of the filamentary article being coiled by the coiling machine, disconnecting the motive power from the coiling machine when a length of the filamentary article required per coil is recorded by the measuring means, allowing the coiling machine to coast to a stop, and starting the measurement of the next successive predetermined length of the article at the beginning of the period during which the coiling machine coasts to a stop.

3. The method of controlling a machine for coiling filamentary articles to produce coils of

55 uniform length, which comprises applying motive power to such a coiling machine to coil a filamentary article, simultaneously measuring the length of the article being coiled by the machine, disconnecting the motive power from the machine when a length of the filamentary article required per coil is recorded by the measuring means, allowing the coiling machine to coast to a stop, and simultaneously resetting the measuring means to its starting position when the motive power is disconnected from the machine so that

the measuring means starts the measurement of the next successive predetermined length of the article at the beginning of the period during which the coiling machine coasts to a stop, whereby each successive driven period and its 5 associated coasting period of the machine produce coils of uniform length.
